UNITED STATES PATENT OFFICE.

JOSEPH G. HUTCHINSON, OF ATTLEBOROUGH, MASSACHUSETTS.

DESIGN FOR A DISPLAY SHOW-CASE.

SPECIFICATION forming part of Design No. 32,114, dated January 16, 1900.

Application filed November 13, 1899. Serial No. 736,885. Term of patent 31 years.

To all whom it may concern:

Be it known that I, JOSEPH G. HUTCHINSON, a citizen of the United States, residing at Attleborough, in the county of Bristol and State of Massachusetts, have invented and produced a new and original Design for a Display Show-Case, of which the following is a specification, reference being had to the accompanying drawings, forming a part thereof.

Figure 1 is a plan view of the display show-case, showing my new design. Fig. 2 is a sectional view on line xx of Fig. 1.

My design consists of a display show-case having a circular concavous body, a circular periphery with an outwardly-curved center and beveled upper and lower edges, a stem and ring extending outward from said peripheral center, a series of radial ribs arranged and disposed as shown in Fig. 1, said ribs

forming sector-shaped receptacles, and a 20 transparent circular disk.

In the drawings, A represents the case, a the stem, and a' the ring.

B represents the disk, and $c c c$ the radial ribs, forming the sector-receptacles $e e e$. 25

Having described my invention, what I claim as new, and desire to secure by Letters Patent, is—

The design for a display show-case; as herein shown and described. 30

In testimony whereof I have signed my name to this specification in the presence of two subscribing witnesses.

JOSEPH G. HUTCHINSON.

Witnesses;

HENRY MARSH, Jr.,
DENNIS H. PHENDON.
